(57) **CLAIM**

The ornamental design for a bottle stopper, as shown and described.

DESCRIPTION

FIG. 1 is a front elevation view of a bottle stopper showing my new design; the rear view being a mirror image thereof; FIG. 2 is a left side elevation view of the bottle stopper of FIG. 1;

FIG. 3 is a right side elevation view of the bottle stopper of FIG. 1;

FIG. 4 is a top view of the bottle stopper of FIG. 1;

FIG. 5 is a bottom view of the bottle stopper of FIG. 1;

FIG. 6 is a bottom perspective view of the bottle stopper of FIG. 1; and,

FIG. 7 is a cross-sectional view of the bottle stopper; taken in the direction of line 7-7 on FIG. 4.

1 Claim, 3 Drawing Sheets(56)
